INSULATING LEADING-IN CONDUCTOR

Daniel S. Gustin, Bloomfield, N. J., assignor, by
mesne assignments, to Westinghouse Electric
and Manufacturing Company, East Pittsburgh,
Pa., a corporation of Pennsylvania

Application April 22, 1936, Serial No. 75,745

2 Claims. (Cl. 176—126)

- My invention relates to electric vapor discharge lamps and particularly to the leading-in conductors therefor which supply electrical energy to at least one of the electrodes.
- 5 Lamps of this general type are well known to the art wherein a discharge occurs between two spaced electrodes due to ionization of a vaporizable material, such for example, as mercury. Because of the necessity for a substantial spacing 10 between the electrodes they are normally disposed at opposite ends of a tubular envelope. Also in order to render the lamp readily adaptable to the usual commercial socket it has been customary to supply electrical energy to the respective electrodes through suitable leading-in 15 conductors which are sealed through the glass wall of the envelope at one end of the envelope where they are connected to the threaded base of the lamp.
- 20 This accordingly necessitates one of the leading-in conductors extending longitudinally of the envelope from the end provided with the threaded base to the oppositely disposed electrode and in order to prevent oxidation or severance of the conductor it is usually disposed internally of the envelope. To prevent a discharge 25 from the leading-in conductor to the electrode carrying opposite instantaneous polarity it has been customary to insulate the portion of the leading-in conductor disposed internally of the envelope with refractory or glass tubes.
- 20 These tubes surround the leading-in conductor and at their lower end are secured to the usual press portion of the envelope either by 35 fusion or by refractory pastes which must be dried out before or during exhausting of the envelope. Not only is the refractory paste a source of impurities and subject to cracking with resultant electrical leakage, but the utilization of such 40 tubes restricts the leading-in conductor to straight sections thus making positioning thereof within the envelope exceedingly difficult.
- In addition the construction is of a very fragile 45 nature requiring strengthening of the seal with the envelope in the event the tube is sealed thereto and eliminating the employment of the tube as a support for one of the electrodes. Moreover, it is practically impossible to bend or shape the leading-in conductor to any desired configuration.
- 50 It is accordingly an object of my present invention to provide an electric vapor discharge lamp provided with a leading-in conductor disposed internally of the envelope having an insulating sheathing fused thereto throughout sub-
- stantially its entire length thus making for an exceptionally rigid construction which is not readily destroyed during handling or operation of the lamp.
- Another object of my present invention is the 5 method of constructing an electric vapor discharge lamp wherein the leading-in conductor for supplying electrical energy to one of the electrodes is provided with a vitreous sheathing fused thereto throughout its entire length between the 10 oppositely disposed electrodes which may be readily bent and shaped to any desired configuration internally of the envelope.
- Another object of my present invention is the provision of an electric vapor discharge lamp 15 provided with a leading-in conductor disposed internally of the envelope having an insulating sheathing of vitreous material fused thereto throughout substantially its entire length to form a rigid support for one of the electrodes 20 of the lamp.
- A further object of my present invention is the provision of a leading-in conductor for an electric vapor discharge lamp provided with a sheathing of vitreous material fused thereto 25 throughout substantially its entire length.
- Still further objects of my present invention will become obvious to those skilled in the art by reference to the accompanying drawing wherein:
- 30 Figure 1 is an elevational view in cross-section of an electric vapor discharge lamp constructed in accordance with my present invention.
- Fig. 2 is a cross-sectional view taken on the line II—II of Fig. 1, and
- 35 Fig. 3 is a cross-sectional view taken on the line III—III of Fig. 1.
- Referring now to the drawing in detail, I have shown in Fig. 1 an electric vapor discharge lamp comprising a vitreous envelope 4, such as hard 40 glass, Pyrex, quartz, or the like capable of withstanding the extremely high temperatures of operation of the lamp, and a quantity of easily vaporizable material, such as a globule of mercury 5 is disposed therein as well as a small quantity of rare gas to facilitate starting, if desired. A pair of electrodes 6 and 7 of any suitable type, such for example as a tungsten helix having a coiled coil wound transversely of the helical wire, 50 are disposed within the envelope 4. The lower electrode 6 is supported by a leading-in conductor 8 sealed into a press portion or the like 9 of the envelope 4 which extends to the shell portion of a standard type screw base 10 for supplying 55

electrical energy from a suitable commercial source of supply (not shown) to the electrode.

The base 10 is suitably cemented to the envelope 4 by a good heat conserving cement, such as an asbestos magnesium oxide admixture and similarly cemented to the opposite end of the envelope is a metallic cap 12 so as to prevent cooling and condensation of the mercury 5 at the ends of the envelope during operation of the lamp. Also disposed adjacent the lower electrode 6 is a starting tip 13 of tungsten which is connected by a sealed-in leading-in conductor 14 to one end of a starting resistance 15 embedded within the base 10.

In order to form a rigid support for the upper electrode 7 as well as to supply electrical energy thereto a leading-in conductor 16 of suitable metal, such as molybdenum, is sealed into the portion 9 of the envelope which is connected to the center contact point of the base 10 and extends longitudinally of the interior of the envelope 4 where it is bent transversely thereof with its free end contacting the wall of the envelope. The electrode 7 is secured to this transverse portion of the leading-in conductor 16 in any suitable manner, such as by welding, at a point coinciding with the longitudinal axis of the envelope 4 so as to be positioned opposite the coaxially disposed lower electrode 6.

Also joined to the transverse portion of the leading-in conductor 16 at the point of connection of the electrode 7 therewith is a cross brace 17 extending at right angles to the leading-in conductor 16 as shown more clearly in Fig. 2 with the ends thereof slightly bent and contacting the walls of the envelope 4. Thus substantially a four point cross is formed, three points of which contact the walls of the envelope at 90° with respect to each other to maintain the electrode 7 in the center of the envelope.

However, due to the length of the leading-in conductor 16 longitudinally of the envelope and the fact it does not contact the walls thereof this would not only allow shifting of the upper electrode 7, but would render the support thereof exceedingly fragile in the absence of my novel construction.

Accordingly I first form the metallic leading-in conductor 16 by surrounding the same while in a straight section with a thin tubing of vitreous material which may be of the same composition as that of the envelope. I then heat this tubing to such a temperature as to fuse the same to the leading-in conductor throughout substantially its entire length to form an integral sheathing 18. The integral sheathed leading-in conductor is then heated at desired locations and bent to form not only the transverse portion previously mentioned, but also an angular portion shown at 19 after which the leading-in conductor together with the electrode 7 and the cross brace 17 secured thereto is disposed within the envelope. Due to the fused sheathing 18 being of the same composition as the envelope it readily fuses with the portion 9 of the latter and a perfect seal is formed. Since the leading-in conductor 16 with its integral sheathing 18 is bent and formed prior to its fusion with the envelope it is disposed out of the path of discharge 70 between the oppositely disposed electrodes 6 and 7 when inserted in the envelope.

Moreover, a rigid support is thus formed by the leading-in conductor 16 for the electrode 7 and the fused sheathing integral therewith, being fused the entire length of the leading-in

conductor between the electrodes 6 and 7, it is not deleteriously affected by the discharge or the high temperature of the metallic vapor present during operation. After assembly of the various parts the envelope 4 is suitably evacuated in the usual manner and the globule of mercury 5 together with a rare gas inserted prior to sealing off at the tip, such as shown at 20.

The upper cap 12 is then cemented to the upper end and prior to connection of the base 10 to the envelope the other end of the starting resistance element 15 is connected to the leading-in conductor 16 and thus embedded in the base 10 upon its being cemented to the lower end of the envelope 4 to complete the lamp.

It thus becomes obvious to those skilled in the art that I have provided an electric vapor discharge lamp having a leading-in conductor therefor which is provided with a sheathing of vitreous material fused thereto throughout substantially its entire length thus forming a rigid construction for supporting at least one of the electrodes of the lamp and maintaining the same in a fixed position within the lamp. Furthermore, due to the rigidity of the leading-in conductor with its integral sheathing the possibility of disruption or severance thereof or destruction of the seal with the envelope due to handling of the tube or during operation thereof is substantially eliminated.

Although I have shown and described one specific embodiment of my present invention I do not desire to be limited thereto as various other modifications of the same may be made without departing from the spirit and scope of the appended claims.

What is claimed is:

1. An electric vapor discharge lamp comprising a vitreous envelope provided with a vaporizable material therein and having a press forming a seal, a pair of oppositely disposed electrodes mounted within said envelope, and means for supplying electrical energy to said electrodes for causing a discharge therebetween including a leading-in conductor sealed into said press and offset to position said conductor in close proximity to the interior surface of said envelope out of the discharge zone between said electrodes and extending in the direction of the longitudinal axis of said envelope, said leading-in conductor having its extremity disposed transversely of said envelope and contacting the wall thereof to rigidly fix the position of said leading-in conductor, an insulated sheathing fused to said press and to the longitudinally extending portion of said leading-in conductor to increase the rigidity thereof, one of said electrodes being connected to the transversely positioned unsheathed portion of said leading-in conductor coaxially with respect to the longitudinal axis of said envelope and a base provided with a sleeve portion of low heat conductivity surrounding the seal forming press to prevent condensation of the vaporizable material during operation of said lamp.

2. An electric discharge lamp comprising a vitreous envelope provided with a vaporizable material therein and having a press forming a seal, a pair of oppositely disposed electrodes within said envelope, and means for supplying electrical energy to said electrodes for causing a discharge therebetween including a leading-in conductor sealed to said press and offset to position said conductor in close proximity to the interior surface of said envelope out of the discharge zone between said electrodes and extend-

ing in the direction of the longitudinal axis of said envelope, said leading-in conductor having its extremity disposed transversely of said envelope and contacting the wall thereof, a member normally disposed with respect to the transversely extending portion of said leading-in conductor and having its extremities contacting the interior wall of said envelope and cooperating with the transversely extending portion of said leading-in conductor to rigidly fix the position of the latter interiorly of said envelope, an insulated sheathing fused to said press and to the longitudinally extending portion of said leading-in conductor to increase the rigidity thereof and to prevent the occurrence of a discharge between said leading-in conductor and the electrode disposed adjacent said press, one of said electrodes

being connected to the transversely positioned unsheathed portion of said leading-in conductor at the intersection of said member normally disposed with respect to the transversely extending unsheathed portion of said leading-in conductor, and a base provided with a sleeve portion of low heat conductivity surrounding the seal forming press to prevent condensation of the vaporizable material during operation of said lamp, and said sleeve portion being secured to said envelope and extending an appreciable distance longitudinally thereof to form a shield for one of said electrodes to prevent emanation of radiations from said incandescent electrode during operation of said lamp.

DANIEL S. GUSTIN.
